UNITED STATES PATENT OFFICE.

CHARLES E. MARTIN, OF MANSFIELD, OHIO.

REMOVABLE BARREL-HEAD.

1,160,740.

Specification of Letters Patent.

Patented Nov. 16, 1915.

Application filed September 9, 1914. Serial No. 860,842.

To all whom it may concern:

Be it known that I, CHARLES E. MARTIN, a citizen of the United States of America, residing at Mansfield, in the county of Rich-
5 land and State of Ohio, have invented cer-
tain new and useful Improvements in Re-
movable Barrel-Heads, of which the follow-
ing is a specification.

This invention relates to certain new and
10 useful improvements in removable barrel
heads, particularly for use with barrels used
to store or transport bottled or bulk goods,
and the primary object of the invention is
to provide a head which can be easily ap-
15 plied to and removed from the barrel with-
out disturbing the usual barrel hoops.

A further object of the invention is to
provide a head which is formed in collapsible
20 or contractible sections that are provided
with interlocking connections at their ad-
jacent edges so as to effectively unite the
sections at their said edges and to provide
a strong and rigid connection therebetween.

A still further object of the invention is
25 to provide improved means for locking the
sections against contractile or collapsible
movement, and means of adjusting the sec-
tions comprising the barrel head to fit the
croze groove of barrels, varying in diameter.

30 Other objects of the invention are to pro-
vide a simple economical and strong head
and lock of serviceable and practical struc-
ture.

In the drawings: Figure 1 is a top plan
35 view of the invention showing the parts in
locked position; Fig. 2 is a similar view
showing the parts in unlocked position; Fig.
3 is a section on the line A—A of Fig. 1
with the barrel omitted; Fig. 4 is a frag-
40 mentary side elevation partly broken away
and shown in section on the line B—B of
Fig. 1; Fig. 5 is a plan view of the sec-
tions comprising the barrel head showing a
modified means of adjustably connecting one
45 end of the sections together.

In accordance with the present invention
the head is preferably formed of sheet metal
comprising two segmental or semi-circular
50 sections 1 and 2 pivoted together by means
of a screw 3 or the like. The inner or
straight side edge of the section 2 is offset
as indicated at 5 and is received in a channel
4 which latter is formed by bending the in-
55 inner or straight side edge of the section 1
back upon itself at 4' and then outwardly at

6, whereby the channel 4 is formed between
the parts 6 and 4' which latter conjointly de-
fine a substantially U-shaped configuration
in cross section. The curved edge of each
section is rolled over or curled at 7 prefer-
ably in an outward direction, the curled
edges 7 being received in the usual croze
groove 8 of the barrel.

For the purpose of holding the sections 1
and 2 expanded and thereby retaining the 65
curled edges 7 within the croze groove 8, a
locking device is employed, which embodies
a pair of toggle levers 9 and 10 pivoted at
their outer ends at 11 and 12 respectively
and pivotally connected together at their in-
70 ner ends at 13. When the toggle levers are
moved toward the center of the head, the
sections 1 and 2 will be contracted at their
free portions or ends by virtue of the sec-
tions moving toward each other about the 75
pivoting screw 3, and when the toggle levers
are moved outwardly toward the periphery
of the head, the sections will be relatively
spread or expanded at their free portions
or ends. Preferably the toggle levers can 80
move to the position shown in Fig. 1 in
which their mutual or common pivotal con-
nection 13 is past the dead center, which lat-
ter is defined by a line drawn between the
pivot points 11 and 12.

For the purpose of holding the toggle le-
vers 9 and 10 in locking position, a locking
lever 14 is provided and is pivoted at 18
to the section 1. The inner end of the tog-
gle lever 9 is turned at right angles at 16 90
to form a stop, and, when the toggle levers
are in locking position, is engaged with an
ear 17 formed on the outer or free end of the
locking lever 14. The outer or free end of
the locking lever is curved to form a shoul-
95 der or abutment 15, which engages with and
rides on the inner side edge of the toggle
lever 10 so as to positively move the toggle
levers to locking position, the movement of
the lever 14 to locking position being limit-
ed by engagement of its ear 17 with the stop
16 of the toggle lever 9. The outward move-
ment of the toggle levers is limited by en-
gagement with the curled edges 7.

If desired registering apertures 17' may 105
be formed in the ear 17 and stop 16 to en-
able fastening or sealing means such as a
wire to be passed therethrough so as to posi-
tively hold the parts locked.

The free end of the bent part 6 of section 110

1 is preferably turned over to form a strengthening and reinforcing rib 19 as depicted in Fig. 3.

In the modification shown in Fig. 5, I secure two L shaped brackets 19' and 20 to the sections 1 and 2 and provide apertures in the upstanding portions. A bolt 21 having both ends threaded is inserted in the apertures thereby connecting the sections. Lock 10 nuts 22 and 23 engage the upstanding portion of the L shape brackets and hold the section in any adjusted position.

Attention is called to the fact that by providing means of expanding or contracting 15 the ends of the section that are provided with the adjustable connecting device, (as shown in Fig. 5) that the section can be made to exactly fit the croze groove in barrels of varying sizes.

20 What is claimed is:

1. In a barrel head, a pair of pivotally connected sections, one of said sections having a channel which receives the adjacent edge of the other section, a pair of toggle levers pivoted together and pivotally connected to the respective sections, and a locking lever pivoted to one of the sections to engage with one of the levers to hold the latter in locking position.
2. In a barrel head, a pair of pivotally connected sections, one of said sections having its inner edge doubled over upon itself and then bent outwardly to form a channel of U-shape in cross-section which channel receives the inner edge of the other section, and means to hold the sections against movement on their said pivotal connection.
3. In a barrel head, a pair of pivotally connected sections, a pair of toggle levers

pivoted together and pivoted to the respective sections, a locking lever pivoted to one of the sections and having a part to engage the inner edge of one of the toggle levers to move both to locking position, an ear on the locking lever and a stop on one of the toggle levers to engage the ear to restrict the extent of movement of the locking lever to locking position.

4. In a barrel head, a pair of pivotally connected sections, a pair of toggle levers pivoted together and pivoted to the respective sections, and a locking lever pivoted to one of the sections and engaged with one of the levers to hold both of the levers locked.

5. In a barrel head, a pair of pivotally connected sections having their outer edges curled to be received in the croze groove of a barrel, means to hold the sections against pivotal movement, and means to expand the sections to frictionally contact with the 60 croze groove.

6. In a barrel head, a pair of pivotally connected sections, toggle levers pivoted together and to the respective sections, and means to lock the toggle levers against movement.

7. In a barrel head, a pair of pivotally connected sections, a toggle device pivoted to the respective sections and movable past dead center to relatively expand the sections, and means to hold the device locked.

In testimony whereof I affix my signature in presence of two witnesses.

CHARLES E. MARTIN.
